SOUND TRANSLATING APPARATUS

Harry F. Olson, Princeton, N. J., assignor to Radio Corporation of America, a corporation of Delaware

Application May 1, 1951, Serial No. 223,865

11 Claims. (Cl. 181—31)

1
The present invention relates to sound translating apparatus, and more particularly to an improved loudspeaker and method for converting electrical energy into acoustical energy.

An important consideration in providing high quality sound reproduction is that the sound translating apparatus have uniform acoustical power output over a wide range of sound frequencies. Although many excellent systems have been proposed in the past, the sound reproducing quality of relatively small apparatus in use today, particularly apparatus of the kind used in the home or in places where space is relatively limited, is not too good. In many home instruments, in order to obtain adequate low frequency response, a large open back cabinet is used. Other acoustical systems employ relatively large, closed cabinets, having a base reflex opening for accentuating low frequency acoustical power output. In others, a plurality of loudspeakers are mounted in a single cabinet to provide suitable coverage over a wide frequency range.

The use of a closed back loudspeaker cabinet is, however, generally accepted as superior to that of the open back cabinet for sound reproduction, since the later type of cabinet exhibits a serious resonance which accentuates the acoustical power output at the particular resonant frequency. In addition, the low frequency acoustical power output of the open back cabinet below the resonant frequency of the loudspeaker is highly attenuated.

It is a primary object of the present invention to provide an improved sound translating apparatus the dimensions of which are relatively small and the acoustical power output of which extends over a wide range of useful sound frequencies.

It is also an object of the present invention to provide an improved sound translating device of relatively small dimensions the acoustical power output frequency characteristic of which is comparable to that of larger instruments having excellent sound reproducing qualities.

Another object of the present invention is to improve the sound reproducing qualities of a loudspeaker mounted in a relatively small, closed back cabinet.

Still another object of the present invention is to provide a method of operating a loudspeaker mounted in a closed cabinet which will enhance the sound reproducing qualities thereof.

A further object of the present invention is to provide a method of operating a loudspeaker mounted in a closed cabinet which will extend the acoustical power output frequency range thereof.

2
It is another object of the present invention to provide a sound reproducing apparatus having a closed back cabinet of relatively small dimensions with excellent fidelity over a wide frequency range, and which is also highly efficient in use.

In accordance with the present invention, the sound reproducing apparatus comprises a cabinet structure arranged to provide two acoustically closed chambers. An opening is provided in a 10 wall of the cabinet, between one of the chambers and the exterior of the cabinet. A loudspeaker diaphragm is disposed over this opening and forms a closure therefor. A sound transmitting passage is provided between the chambers and a second 15 loudspeaker diaphragm is mounted in a manner to form a closure therefor. The two loudspeakers are connected to the output stage of a conventional audio frequency amplifier. The loudspeaker mounted between the chambers is 20 adapted particularly to reproduce most efficiently low audio frequency sound waves whereby mechanical coupling between the diaphragms through the air medium common to both diaphragms serves to assist in driving the other dia- 25 phragm in the low frequency range thereby enhancing the sound reproducing quality of the apparatus by extending the overall acoustical power output frequency range.

The novel features characteristic of the present invention, as well as additional objects and advantages thereof, will be understood better from the following detailed description when read in connection with the accompanying drawing, in which

35 Figure 1 is a side view, partly broken away, of a single loudspeaker mounted in a closed back cabinet.

Figure 2 is a wiring diagram of an electrical circuit corresponding to the acoustical network 40 of the vibrating system of the apparatus shown in Figure 1.

Figure 3 shows two curves which indicate the acoustical power output frequency characteristics of a loudspeaker mounted in closed back cabinets of different volumes.

Figure 4 is a side view, partly broken away, of a sound reproducing apparatus in accordance with one embodiment of the present invention.

Figure 5 is a wiring diagram of an electrical network corresponding to the acoustical network of the vibrating system of the apparatus shown in Figure 4.

Figure 6 shows two curves, one of which indicates the electrical impedance frequency characteristic of one of the loudspeakers shown in Fig-

ure 4, and the other of which shows the electrical impedance frequency characteristic of the other loudspeaker.

Figure 7 shows two curves representing a comparison of the acoustical power output frequency characteristics of the apparatus shown in Figures 1 and 4, both cabinets having the same volume,

Figure 8 is a sectional view of a second embodiment of sound reproducing apparatus in accordance with the present invention, and

Figure 9 is a wiring diagram of an electrical network depicting the electrical impedance of the two voice coils of the systems shown in Figures 4 and 8.

Referring more particularly to the drawing, wherein similar reference characters designate corresponding parts throughout, there is shown, in Figure 1, for comparison purposes, a closed back cabinet 1 in which a loudspeaker 3 is mounted with the diaphragm 5 thereof disposed behind an opening 7 provided in a wall 9 of the cabinet so as to form a closure for the opening. The acoustical network for this type of enclosed loudspeaker cabinet may be represented by an electrical circuit diagram, as shown in Figure 2 of the drawing, wherein:

p_1 =the driving pressure of the loudspeaker, which may be calculated from the equation:

$$p_1 = \frac{f M_1}{A_1} \quad (1)$$

where

$$f M_1 = B_1 l_1 i_1;$$

B_1 =magnetic flux density in the air gap;

l_1 =length of the conductor in the voice coil of the loudspeaker; and

i_1 =current in the voice coil of the loudspeaker;

A_1 =area of the cone diaphragm of the loudspeaker;

r_A =acoustical radiation resistance presented to the cone diaphragm of the loudspeaker;

and where

M_1 =inertance of the cone diaphragm, the voice coil and the air load on the cone diaphragm of the loudspeaker;

C_{AS} =acoustical capacitance of the cone diaphragm suspension system;

C_{AC} =acoustical capacitance of the cabinet, as calculated from the equation:

$$C_{AC} = \frac{V}{\rho c^2} \quad (2)$$

where

V =volume of the cabinet;

ρ =density of air; and

c =velocity of sound.

The acoustical volume current in the system is given by the equation:

$$\dot{X}_1 = \frac{p_1}{r_A + j\omega M_1 - \frac{j}{\omega C_{AS}} - \frac{j}{\omega C_{AC}}} \quad (3)$$

where

$$j = \sqrt{-1}$$

$$\omega = 2\pi f$$

f =frequency

The acoustical power output of the system is given by the equation:

$$P = r_A \dot{X}_1^2 \quad (4)$$

Referring to the Equations 3 and 4 above, it will

be seen that the acoustical power output in the low frequency range is influenced by the cabinet volume. As the cabinet volume is decreased, the low frequency cut-off in acoustical power output is increased in frequency.

If, for example, a loudspeaker having a twelve inch diameter diaphragm with a resonant frequency of 70 cycles per second is mounted in a closed back cabinet 1, in the manner shown in Figure 1, the acoustical power output frequency characteristic of the apparatus using cabinets having volumes of 5 and 2 cubic feet, respectively, may be represented by curves as shown in Figure 3. In this family of curves, curve A represents the acoustical power output frequency characteristic for the twelve inch loudspeaker mounted in a five cubic foot cabinet, and curve B represents the acoustical power output frequency characteristic for that same loudspeaker mounted in a two cubic foot cabinet. A comparison of these two curves shows that, in the case of the five cubic foot cabinet, the resonant frequency of the loudspeaker is approximately 100 cycles per second, whereas, in the case of the two cubic foot cabinet, the resonant frequency is approximately 130 cycles per second. A comparison of these two curves shows that, the smaller the cabinet cavity the higher the resonant frequency of the loudspeaker. In either of these cases, the resonant frequency is too high and the acoustical power output falls off rapidly below the resonant frequency thereby reducing the output in the low frequency range, a condition unsuitable for excellent sound reproduction.

On the other hand, if a loudspeaker having a lower resonant frequency were used, for example, one having a 50 cycle per second resonant frequency alone, the resonant frequencies of that loudspeaker mounted in cabinets of 5 and 2 cubic feet volumes, would be respectively, 86 and 120 cycles per second. However, experience has shown that a twelve inch loudspeaker with a 50 cycle resonant frequency is not only difficult to construct but it is also difficult to maintain uniform acoustical power output in the mid-frequency range due to break up of the flexible suspension system for the diaphragm.

The current trend being toward the use of smaller cabinets for sound translating instruments, the present invention is particularly concerned with the improvement in low frequency acoustical power output of conventional types of loudspeakers mounted in closed back cabinets of relatively small volume. For average use, a tolerable cabinet would have a volume of approximately two cubic feet.

In accordance with one embodiment of the present invention, improved sound reproducing quality of relatively small apparatus is obtained by employing an acoustically closed cabinet or walled enclosure 15 having an opening 17 through a wall 19 thereof. A partition 21 having an opening 23 therein is mounted within the cabinet so that it divides the interior into two chambers 25, 27.

A sound reproducer comprising a loudspeaker 29 is mounted with the diaphragm 31 thereof covering the wall opening 17 so that it forms with the cabinet wall a closure for that opening. A second loudspeaker 33 is mounted with the diaphragm 35 thereof covering the partition opening 23 so that it forms with the partition a closure for that opening. Thus, the loudspeaker diaphragms

together with the enclosure walls and the partition provide two acoustically closed chambers.

In one sound reproducing apparatus, made for experimental use, a cabinet having a volume of two cubic feet is provided. A loudspeaker 29 having a twelve inch diameter cone diaphragm 31 and a resonant frequency of 70 cycles per second is mounted behind the opening 17 connecting the chamber 25 with the exterior of the cabinet. A second loudspeaker 33 having a five inch cone diaphragm is mounted with its diaphragm 35 covering the partition opening 23. The partition 21 is arranged in the cabinet 15 so that an acoustically closed chamber 25 of one-half cubic foot volume is provided behind the larger diaphragm. The other chamber 27 has a volume of one and one-half cubic feet. The respective electro-mechanical driving means for the loudspeakers 29, 33 are connected electrically in series with a common source of energy provided by a conventional audio frequency amplifier (not shown). If desired, the electro-mechanical driving means may be connected electrically in parallel with the source of energy. The acoustical network for this arrangement is shown by an electrical circuit diagram, such as that illustrated in Figure 5 of the drawing, wherein:

p_1 =driving pressure of the large loudspeaker, as determined from the equation,

$$p_1 = \frac{f_{M1}}{A_1} \quad (5)$$

where

$$f_{M1} = B_1 l_1 i_1;$$

B_1 =flux density in the air gap in the large loudspeaker;

l_1 =length of the conductor in the voice coil of the large loudspeaker;

i_1 =current in the voice coil of the large loudspeaker; and

A_1 =area of the cone diaphragm of the large loudspeaker;

p_2 =driving pressure of the small loudspeaker, as determined from the equation:

$$p_2 = \frac{f_{M2}}{A_2} \quad (6)$$

where

$$f_{M2} = B_2 l_2 i_2;$$

B_2 =flux density in the air gap in the small loudspeaker;

l_2 =length of the conductor in the voice coil of the small loudspeaker;

i_2 =current in the voice coil of the small loudspeaker; and

A_2 =area of the cone diaphragm of the small loudspeaker;

r_A =acoustical radiation resistance presented to the cone diaphragm of the large loudspeaker;

M_{S1} =inertance of the cone diaphragm, the voice coil and the air load on the diaphragm of the large loudspeaker;

M_{S2} =inertance of the cone diaphragm, the voice coil and the air load on the diaphragm of the small loudspeaker;

C_{AS1} =acoustical capacitance of the diaphragm suspension of the large loudspeaker;

C_{AS2} =acoustical capacitance of the diaphragm suspension of the small loudspeaker;

C_{AS3} =acoustical capacitance of the volume of

air in the small chamber common to both loudspeakers, as determined from the equation

$$C_{AS3} = \frac{V_3}{\rho c^2} \quad (7)$$

where

V_3 =volume of the air in the small chamber common to both loudspeakers;

ρ =density of air; and

c =velocity of sound;

C_{AS4} =acoustical capacitance of the volume of air in the large chamber, as determined from the equation

$$C_{AS4} = \frac{V_4}{\rho c^2} \quad (8)$$

where V_4 =volume of the air in the larger chamber.

The volume current in branch 1 of the electrical circuit is given by the equation:

$$\dot{X}_1 = \frac{p_1(Z_{A2} + Z_{A3})}{D} + \frac{p_2(Z_{A2})}{D} \quad (9)$$

where

$$D = Z_{A1}Z_{A2} + Z_{A1}Z_{A3} + Z_{A2}Z_{A3}$$

(The acoustical impedances

$$Z_{A1}, Z_{A2} \text{ and } Z_{A3}$$

refer to the acoustical impedances of the branches 1, 2 and 3 respectively of the network of Figure 5.)

The acoustical impedance of branch 1 of Figure 5 is given by the equation:

$$Z_{A1} = r_A + j\omega M_{S1} - \frac{j}{\omega C_{AS1}} \quad (10)$$

The acoustical impedance of branch 2 of Figure 5 is given by the equation:

$$Z_{A2} = -\frac{j}{\omega C_{AS2}} \quad (11)$$

The acoustical impedance of branch 3 of Figure 5 is given by the equation:

$$Z_{A3} = j\omega M_2 - \frac{j}{\omega C_{AS2}} - \frac{j}{\omega C_{AS4}} \quad (12)$$

The volume current in branch 3 is given by the equation:

$$\dot{X}_3 = \frac{p_2(Z_{A1} + Z_{A2})}{D} + \frac{p_1(Z_{A2})}{D} \quad (13)$$

Since the two loudspeakers are connected in series, $i_1 = i_2$, and

$$\frac{p_1}{p_2} = \frac{B_1 l_1 A_2}{B_2 l_2 A_1} = K \quad (14)$$

where K =constant.

The acoustical impedance at p_1 is given by the equation:

$$Z'_{A1} = \frac{D}{Z_{A2} + \frac{Z_{A2}}{K} + Z_{A3}} \quad (15)$$

The acoustical impedance at p_2 is given by the equation:

$$Z'_{A2} = \frac{D}{Z_{A2} + Z_{A1} + KZ_{A2}} \quad (16)$$

The electrical circuit of the voice coils of the large and small loudspeaker connected in series is shown in Figure 9. The electrical impedance and the quantities in this circuit will now be defined. In the electrical circuit, the electrical im-

pedance of the two loudspeakers connected in series is given by the equation:

$$Z_{ET} = r_{E1} + j\omega L_1 + Z_{EM1} + r_{E2} + j\omega L_2 + Z_{EM2} \quad (17)$$

where

r_{E1} =electrical resistance of the voice coil of the large loudspeaker;

L_1 =inductance of the voice coil of the large loudspeaker;

r_{E2} =electrical resistance of the voice coil of the small loudspeaker;

L_2 =inductance of the voice coil of the small loudspeaker;

Z_{EM1} =motional electrical impedance of the voice coil of the large loudspeaker. The motional electrical impedance of the voice coil of the large loudspeaker is the electrical impedance due to motion of the voice coil as determined from the equation:

$$Z_{EM1} = \frac{(B_1 l_1)^2}{Z_{A1} A_1^2} \quad (18)$$

Z_{EM2} =motional electrical impedance of the voice coil of the small loudspeaker. The motional electrical impedance of the voice coil of the small loudspeaker is given by the equation:

$$Z_{EM2} = \frac{(B_2 l_2)^2}{Z_{A2} A_2^2} \quad (19)$$

The current through the voice coils is given by the equation:

$$i = \frac{e}{r_{ET}} \quad (20)$$

where e =voltage applied to the voice coils.

The acoustical power output is the power output delivered by the diaphragm of the large loudspeaker and is given by the equation:

$$P = r_A X_1^2 \quad (21)$$

Employing Equations 9 to 21 inclusive it is possible to determine the acoustical power output of the system. The above analysis shows that it is possible to extend the low frequency range by the use of a second loudspeaker.

Several models of this system have been built. As a typical example, in one model, the diameter of the cone diaphragm of the large radiating loudspeaker was 12 inches and the diameter of the cone diaphragm of the small driving loudspeaker was 5 inches. The mass of the voice coil of the small loudspeaker was about twice that of the large loudspeaker. The flux density in the air gap was 12,000 gauss as compared to 10,000 for the large loudspeaker. The resonant frequency of the small loudspeaker was 50 cycles per second and the large loudspeaker 80 cycles per second. The total cabinet volume was 2 cubic feet. The volume behind the small loudspeaker was 1 1/2 cubic feet. The volume between the two loudspeakers was less than 1/2 cubic foot. Employing this system, an examination of the acoustical circuit shown in Figure 5 and Equations 9 to 20 inclusive, discloses that the load on the back of the large loudspeaker diaphragm is very small in the region from 50 to 300 cycles per second. Thus, the acoustical power output conditions, as far as the large loudspeaker is concerned, are practically the same as if the large loudspeaker were mounted in a cabinet having a very large volume. The electrical impedance frequency characteristic of the large speaker alone is shown by curve A in Figure 6. The electrical impedance frequency characteristic of the small loudspeaker mounted in a cabinet of one and one half cubic

feet is shown by curve B in Figure 6. In the region above 300 cycles per second, the acoustical impedance of the chamber of one half cubic foot volume is small compared to the acoustical impedance of the large diaphragm and, therefore, does not influence the acoustical power output. It will be observed from the curves shown in Figure 6 that above 300 cycles per second the electrical impedance of the small loudspeaker is very small compared to the electrical impedance of the large loudspeaker. As a result, since the two loudspeakers are connected in series practically all the input electrical power is fed to the large loudspeaker in the region above 300 cycles. Under the above conditions the large loudspeaker operates alone and in the conventional manner above 300 cycles per second.

The acoustical power output frequency characteristic for the combination of closely coupled loudspeakers mounted in a cabinet of two cubic feet volume is shown by curve A in Figure 7. For comparison purposes, the acoustical power output characteristic for the 12 inch loudspeaker mounted alone in a 2 cubic foot cabinet, as shown by curve B in Figure 3, is superimposed on curve A in Figure 7. It will be seen from a comparison of these two curves that there is considerable extension of the low frequency acoustical power output. This is explained by the introduction of the smaller loudspeaker and coupling it mechanically with the large loudspeaker through the enclosed volume of air in the small chamber. Thus, in the region below 300 cycles, the small loudspeaker, which is adapted to reproduce most efficiently sound waves of relatively low audio frequencies in the desired range of frequencies, functions as a supplementary driving element for the large loudspeaker, which is adapted to reproduce efficiently sound waves over that entire range. Effectively, the sound pressure developed by the small loudspeaker reduces the acoustical impedance presented to the back of the large loudspeaker over that which would exist if the large loudspeaker operated directly into the entire cabinet. In the example referred to above, over the frequency range from 50 to 300 cycles per second, the acoustical impedance presented to the back of the large loudspeaker is practically the same as that of a very large cabinet.

From the foregoing description, it will be apparent that the present invention provides an improved sound reproducing system for completely closed loudspeaker cabinets of relatively small dimensions.

It will be obvious to persons skilled in the art that various modifications and changes in the sound reproducing apparatus shown and described herein are possible within the spirit of the present invention. For example, as shown in Figure 8, the partition 24 may be disposed diagonally of the interior of the cabinet. On the other hand, two separate, acoustically closed cabinets may be provided with means for transmitting sound from one of the loudspeakers mounted in one cabinet to the chamber provided by the other cabinet. Other changes of like nature will, of course, readily suggest themselves. Therefore, it is desired that the particular forms of the present invention shown and described herein shall be considered as illustrative and not as limiting.

What is claimed is:

1. Sound reproducing apparatus comprising a walled enclosure, means dividing the interior of said enclosure into separate acoustically closed chambers, an exterior wall of said enclosure

having an opening therein connecting one of said chambers with the exterior of said enclosure, said dividing means including an opening therein defining a sound passage between said chambers, sound reproducing means including a diaphragm mounted over each of said openings and forming a closure therefor, and electro-mechanical driving means connected to each of said diaphragms.

2. The invention as defined in claim 1 wherein said sound reproducing means comprises a plurality of closely coupled loudspeakers, one of said loudspeakers being adapted to reproduce efficiently sound waves over the entire range of desired audio frequencies and the other of said loudspeakers being adapted to reproduce most efficiently sound waves of relatively low audio frequency in said range.

3. The invention as defined in claim 1 wherein the volume of the chamber common to both said diaphragms is substantially smaller than the volume of the other of said chambers.

4. The invention as defined in claim 1 wherein said electro-mechanical driving means for each of said diaphragms is connected to a common source of electrical energy.

5. The invention as defined in claim 1 wherein one of said diaphragms is larger in area than the other of said diaphragms.

6. Sound reproducing apparatus comprising a walled enclosure, means including a partition having an opening, a loudspeaker diaphragm covering said opening, said last named means dividing the interior of said enclosure into two acoustically closed chambers, one wall of said enclosure having an opening therein connecting one of said chambers with the exterior of said enclosure, and a second loudspeaker diaphragm mounted over said opening.

7. Sound reproducing apparatus comprising walled enclosures defining first and second acoustically closed chambers, said first and second

chambers having a common wall, the first one of said chambers having an opening in an exterior wall thereof, a loudspeaker including a diaphragm mounted over said opening and forming a closure therefor, an opening in said common wall, a second loudspeaker including a diaphragm mounted in said opening in said common wall and forming a closure therefor.

8. Sound reproducing apparatus as defined in claim 7 wherein said enclosures are dimensioned to provide acoustically closed chambers of different sizes.

9. Sound reproducing apparatus as defined in claim 8 wherein the enclosure having an opening in the exterior wall thereof is dimensioned to provide the smaller one of said chambers.

10. Sound reproducing apparatus as defined in claim 9 wherein one of said loudspeakers is adapted to reproduce most efficiently low audio frequency sound waves, said one of said loudspeakers having its said diaphragm mounted over the opening in the enclosure having the smaller one of said chambers.

11. Sound reproducing apparatus as defined in claim 10 wherein said loudspeakers are connected electrically in series.
